United States Patent Office

Des. 180,390
Patented June 4, 1957

180,390

COMBINED TRAFFIC SIGNAL AND ADVERTISING SIGN

Rea M. Bruner, Colorado Springs, Colo.

Application March 7, 1956, Serial No. 40,507

Term of patent 14 years

(Cl. D72—1)

FIG. 1.

FIG. 2.

FIG. 3.

Figure 1 is a perspective view of a combined traffic signal and advertising sign showing my new design;

Figure 2 is an elevational view of any side thereof;

Fig. 3 is a top view thereof.

I claim:

The ornamental design for a combined traffic signal and advertising sign, substantially as shown.
